UNITED STATES PATENT OFFICE.

EDWARD DES ENFANTS, SR., OF LUDINGTON, MICHIGAN, ASSIGNOR TO HANDY THINGS MANUFACTURING COMPANY, OF LUDINGTON, MICHIGAN, A CORPORATION OF MICHIGAN.

GLASS SCRAPER.

Application filed October 3, 1927. Serial No. 223,560.

This invention relates to a scraper of the type commonly used in scraping glass to remove paint, varnish or other material which may be deposited thereon. It is a primary object and purpose of the present invention to construct a scraper of the type noted in a simple and novel manner whereby bolts, screws or the like for fastening the parts together are eliminated and the scraper member, which consists of a blade similar to a safety razor blade, may be clamped in place, a scraper being provided which comprises two parts only in addition to the blade used and which is capable of sustaining the usage to which a device of this character is put in service.

An understanding of the invention may be had from the following description taken in connection with the accompanying drawing, 20 in which,

Fig. 1 is a perspective view of the scraper of my invention.

Fig. 2 is a perspective view showing the method of assembly or disassembly of the 25 scraper.

Fig. 3 is a longitudinal vertical section through the scraper in partially disassembled relation.

Fig. 4 is a similar view showing the 30 scraper completely assembled.

Fig. 5 is a fragmentary side elevation illustrating the scraper in partially assembled form, and

Fig. 6 is a similar view showing the 35 scraper fully assembled.

Like reference characters refer to like parts in the different figures of the drawing.

In the construction of the scraper a member of sheet metal is provided of channel form having a web bottom 1 from which two flanges 2 extend upwardly at opposite sides as shown in Fig. 2. At one end of this member a handle section 3 of inverted channel form is attached partially covering the first channel member. In practice the two parts are made integral and formed by suitable dies and tools into the shape shown. The web or bottom 1 directly in front of the handle section 3 has a slot 4 cut therein which is disposed lengthwise of the device.

The opposite end of the channel member is widened and formed into a base plate 5 from which at two spaced apart points

projections 6 of circular outline are pressed upwardly. At each edge of the plate 5 lips 7 are formed and are turned backwardly over the plate to provide clamping clips for a purpose which will later appear. A 60 scraper blade, which may be either a blade such as is used with safety razors or one of a similar though heavier construction, may be placed against the base plate 5. The blade 8 may be sharpened at either one or both longitudinal edges and has openings 9 therein spaced so as to fit over the projections 6 when the blade is placed upon the base plate 5.

The other member of the clamping device 70 is also formed of sheet metal in channel form, having an upper side or web 10 with downwardly extending flanges 11, while at one end it is likewise widened and made into a clamping plate 12, the width being such that it may be received under the clamping clips 7. At the opposite end of the second member the metal is turned downwardly at right angles making an end section 13, which is narrowed to make a narrow connecting section 14, and then terminates in a wider head 15.

With the blade 8 laid upon base plate 5 the section 15 may be passed through the slot 4 by turning the second member of the 85 device at an angle to the first member, as shown in Fig. 2. The narrow connecting section 14 is slightly less in width than the width of the slot 4 so that the second member of the device may be turned back to lie 90 directly over the first member described. When thus positioned, as shown in Fig. 3, the turned down end member comprised of sections 13, 14 and 15 is located at the front end of the slot 4 and the upper member of 95 the device may then be lowered to substantially the position shown in Fig. 5, whereupon the rear edges of the clamping plate 12 will come directly in front of the clamping clips 7. Then by pressing against 100 the section 15 so as to move the second member bodily to the rear, the clamping plate 12 will be drawn to the rear underneath the overhanging clips 7 or until stopped by the engagement of the end section 13 with the 105 supplementary handle portion 3, as shown in Fig. 4. In this position the base plate 5 will lie directly under the clamping plate 12 and will be clamped against the blade 8, holding it securely against movement 110

and against any disengagement from the projections 6, as is evident.

The disassembly of the construction is merely a reversal of the operations described 5 consisting in the movement of the upper member of the device longitudinally, which movement may be effected by pressure against the rear side of the section 15 so as to move the narrow connecting section 14 10 lengthwise of the slot 4. This frees the clamping plate 12 of the clamping clips 7 so that it may be lifted to the position shown in Fig. 3 and the blade 8 removed for sharpening or replacement.

15 The construction described is very simple but practical. The elimination of screws or other securing devices is a very desirable feature of the present invention reducing the number of parts and eliminating considerable time and trouble in assembling. The 20 device consists of but two parts for holding the blade.

It will be noted that the handle portion 1 of the device is indented transversely as 25 indicated at 16 between the ends of the slot 4. This is for the purpose that on moving the other handle portion 11 with the integral clamping plate 12 longitudinally or to the position shown in dotted lines in Fig. 30 4, the inner edges of the part 15 will engage with the indentations at 16 holding the device in the position shown in dotted lines in Fig. 4. The edge of the blade 8 will be covered by the clamping plate 12 and a 35 guard thus made so that there is no danger of cutting by the blade when the device is not used or when it is carried in the pocket of a workman. It is also evident that the movement of the clamping plate 12 from 40 the position which it occupies when the edge of the blade is exposed, as in Fig. 1, to the dotted line position shown in Fig. 4, removes any material which has collected on the blade ahead of the edge of the clamping 45 plate 12 thereby scraping and cleaning the same from the blade.

These are features of advantage. Paint or putty which adheres to the blade is very quickly and easily removed in this manner.

50 The construction has proved very practical and serviceable. The invention is defined in the appended claims and is to be considered comprehensive of all forms of structure coming within their scope.

55 I claim:

1. A scraper comprising, one member having a handle portion of channel cross section with a slot cut through the web of said handle portion, said handle portion at one 60 end being widened to form a base plate, spaced apart lugs projecting from said base plate, a blade located against the base plate having openings into which said lugs extend, a second member having a handle portion also of channel form inverted with re-

spect to the handle portion of the first member and at one end being widened so as to lie over said blade and base plate, and at the opposite end being formed with an inverted locking member adapted to pass 70 through the slot in the web of the first handle portion, said locking member being slidable lengthwise of said slot, and clamping means on one of said plates with which the other engages on longitudinal sliding 75 movement of the members relative to each other thereby clamping the blade between said plates.

2. A construction comprising the elements in combination defined in claim 1, said locking member comprising a section wider than 80 said slot where said section joins the handle portion to which it is attached, a second section slightly narrower than said slot and a third terminal section wider than the 85 slot, the length of the second and narrowest section being slightly greater than the thickness of the metal from which the first member is made.

3. A device of the class described comprising, two contiguously arranged members having superimposed clamping portions, said members being movable relative to each other, interengaging means on said members near their clamping portions, said means 90 serving when interengaged to retain the clamping portions together and being disengageable by relative sliding movement of the members, and means associated with both members remote from the clamping 95 portions serving as a combined sliding and 100 hinge connection between said members.

4. A device of the class described comprising, two contiguously arranged members having superimposed clamping portions, said members being movable relative to each other, interengaging means on said members near their clamping portions, said 105 means serving when interengaged to retain the clamping portions together and being 110 disengageable by relative sliding movement of the members, and means associated with both members remote from the clamping portions serving as a combined sliding, pivotal and hinged connection.

5. A device of the class described comprising, two contiguously arranged members having superimposed clamping portions, said members being movable relative to each other, interengaging means on said members 120 near their clamping portions, said means serving when interengaged to retain the clamping portions together and being disengageable by relative sliding movement of the members, and means associated with both members remote from the clamping 125 portions serving as a combined sliding, pivotal and hinged connection, said remote means being separable when the members are disposed in angular relation to each other. 130

6. A device of the class described comprising, two relatively movable superimposed members each having a clamping portion, interengaging means on both members 5 near their clamping portions to retain said members in contiguous relation when the means are interengaged and to permit separation of the members when said means are disengaged, an elongated slot in one of said

members, an extension on the other of said members extending through said slot and slideable therein, said extension having a head on the outside of said slot, said head being proportioned to pass through said slot when the members are in angular relation to each other. 10 15

In testimony whereof I affix my signature.
EDWARD DES ENFANTS, Sr.
